UNITED STATES PATENT OFFICE.

JAMES S. THOMPSON, OF PELHAM, NEW YORK.

BRAKE-SHOE MOLD.

Application filed August 1, 1923. Serial No. 655,025.

To all whom it may concern:

Be it known that I, JAMES S. THOMPSON, a citizen of the United States, residing at Pelham, in the county of Westchester and State of New York, have invented certain new and useful Improvements in Brake-Shoe Molds, of which the following is a specification.

This invention relates to the manufacture of brake shoes, and more particularly to the mold in which the shoe is cast, and its object is broadly to enable a brake shoe to be cast in a permanent mold as well as, or better than, it can be cast in a sand mold, and with accompanying reductions in time and cost.

A still further object of my invention is to provide a mold of the character described having improved means for supporting or holding in place in the mold cavity the parts which are to be embedded in the shoe casting.

Other objects of my invention will become apparent as the detail description progresses, reference being had to the accompanying drawings, wherein—

Fig. 1 is a central transverse section taken through a metal mold embodying the novel features of my invention.

Fig. 2 is a central longitudinal section taken on line 2—2 of Fig. 1.

Fig. 3 is a transverse section taken on line 3—3 of Fig. 2.

Fig. 4 is a plan view of the mold shown in Figs. 1, 2 and 3, the cope members of the mold being swung back into their open positions.

Fig. 5 is a central longitudinal section taken through a metal mold for casting brake shoes and it illustrates another form which my invention may take, and

Fig. 6 is a section taken on line 6—6 of Fig. 5.

Referring for the present to Figs. 1 to 4 inclusive of the drawings, the reference character 10 designates a relatively fixed drag member of a mold embodying the novel features of my invention. The mold also comprises two cope members 11 and 12, each of which cope members is provided with outstal^{ing} side lugs 13 pivotally connected by means of pivoting bars 14 to out-standing side lugs 15 formed upon the drag 10. The mold cavity is designated by the reference character 16 and the parting line between the cope members extends longitudi-

nally of the mold and substantially central of the mold cavity. This construction enables the mold to be quickly and easily opened and closed and it also enables the parts which are to be embedded in the shoe casting to be arranged in the mold and held therein in proper positions. The cope members may be brought into the positions indicated by dotted lines in Fig. 1 and indicated by full lines in Fig. 4. It will become apparent, as this description progresses, that the cope members may be closed without injury to and without disarranging certain parts which are customarily embedded in the shoe casting, and that they may be opened for the removal of the shoe casting without damage to any part of the mold. I prefer to provide a pair of clamps 17 for locking the cope members in their closed positions with respect to the drag 10.

The parts which are customarily embedded in the shoe casting are, a steel attaching lug 18 and a steel reinforcing back 19. I have also shown at 20 a sand core which is adapted to form the opening in the attaching lug. I have found it advantageous to assemble the attaching lug, the steel back and the sand core in the manner illustrated in Figs. 1 and 2, the sand core being interposed between the attaching lug and the steel back. To facilitate handling of these assembled parts as a unit, it is preferable to provide a plurality of wire ties 21 which will prevent displacement of any one of the assembled parts with respect to the remainder of the assembled parts. The sand core 20 is adapted to enter a recess 22 formed in the cope members 11 and 12, the recess being formed in a pair of refractory sections 23 and 24 which form parts of the cope members 11 and 12 and which are provided for a purpose hereinafter set forth.

I have provided improved means for supporting in the mold cavity the parts which are to be embedded in the shoe casting. This means comprises a pair of bent wires 25 which are themselves supported by the drag member 10. I prefer to arrange these wires transversely of the mold cavity 16 and, as shown in Fig. 3, I prefer to provide grooves 26 in the upper face of the drag member, in which grooves 26 the ends of the bent wires 25 may rest. The wires 25 are bent to provide shoulders 27 adapted to engage the side walls 28 of the mold cavity to correctly position the wires with respect to

the mold cavity so that humps 29 formed in the wires 25 may engage openings 30 in the steel reinforcing back 19 and thereby correctly position the back longitudinally and laterally of the mold cavity. It is understood, of course, that the wires 25 will support the steel back, and the parts secured to it, in the mold cavity. The wires 25 are enabled to correctly position the steel back 19 longitudinally of the mold cavity as they are arranged to have their humps 29 enter the openings 30 at points adjacent ends of the openings. This construction enables the operator, when he is preparing the mold for the casting operation, to quickly and easily place and position the steel back, attaching lug and the sand core 20 as a unit in the mold cavity. The cope members 11 and 12 may then be brought into and locked in their closed positions after which the mold will be ready for the casting operation. The mold shown in Figs. 1 to 4 inclusive permits a brake shoe to be cast having a substantially uniform texture throughout the body of the shoe. It is for this purpose that the aforementioned refractory sections 23 and 24 are provided in the cope members 11 and 12, the refractory sections 23 and 24 forming substantially all of the mold cavity walls carried by the cope members. The cavity walls of the drag member 10 are formed by a refractory section 32 seated in the drag member. It is apparent that the several refractory sections form substantially the entire walls of the mold cavity and prevent the hot metal from coming into contact with the metal of the mold, thereby protecting the casting from the chilling effect which would result by contact of the hot metal with the metal of the mold. However, the several refractory sections could be made to leave certain portions of the metal of the mold as portions of the walls of the mold cavity if it were desired to cast a shoe having an integral composite wearing face.

In Figs. 5 and 6 I have illustrated another form which my invention may take. In a mold of substantially the same construction as the mold illustrated in Figs. 1 to 4 inclusive, I have shown a pair of rests 33 adapted to stand upon the bottom wall 34 of the mold cavity. The rests 33 support the steel back 19 in a manner similar to that with which the wires 25 support the steel back 19 of the mold shown in Figs. 1 to 4 inclusive. I prefer to provide the rests 33 with lugs 35 adapted to enter the openings 30 in the steel back 19 so that the rests may be employed to correctly position the steel back longitudinally and laterally of the mold cavity. I have provided each of the molds shown in the drawings with a pouring gate 36 and with a plurality of sand vents 37, the sand vents 37 permitting gases

to escape from the mold cavities during a casting operation.

My invention can be employed for making castings other than brake shoes, and I consider myself entitled to make all such changes in the form, construction and arrangement of parts as may be necessary or desirable for this purpose, and for making different kinds, shapes and sizes of brake shoes, which fairly fall within the scope of the following claims.

I claim—

1. A permanent mold for making castings, and comprising a drag and a cope having a mold cavity therein, and means engaging the parting surface of the drag for holding in place in the mold cavity the parts to be embedded in the casting.

2. A mold for casting a brake shoe, and comprising a drag and a cope having a mold cavity therein, and means engaging the parting surface of the drag for supporting in the mold cavity a reinforcing back to be embedded in the shoe casting, said supporting means being adapted to properly position the reinforcing back in the cavity.

3. A permanent mold for making castings, and comprising a drag and a cope having a mold cavity therein, and means for holding in place in the cavity the parts to be embedded in the casting, said means comprising a wire carried by the drag.

4. A permanent mold for making castings, and comprising a drag and a cope having a mold cavity therein, and means extending across the mold cavity and resting on the drag for securing in place in the mold cavity the parts to be embedded in the casting.

5. A mold for casting a brake shoe, and comprising a drag and a cope having a mold cavity therein, and means supported by the drag for properly positioning in the mold cavity a reinforcing back to be embedded in the shoe casting, said means being adapted to engage an opening in the back.

6. A permanent mold for making castings, and comprising a drag and a cope having a mold cavity therein, and means for supporting an element in the mold cavity to be embedded in the casting and comprising wires resting upon the parting surface of the drag.

7. A permanent mold for making castings, and comprising a drag and a cope having a mold cavity therein, and means for supporting an element in the mold cavity to be embedded in the casting and comprising wires resting upon the parting surface of the drag and depressed within the mold cavity.

8. A permanent mold for making castings, and comprising a drag and a cope having a mold cavity therein, a drag having oppositely disposed grooves in its parting

surface, and a wire arranged in said grooves for supporting in the mold cavity an element to be embedded in the casting.

9. A permanent mold for making castings, and comprising a drag and a cope having a mold cavity therein, and a wire extending across the mold cavity and resting on the drag and having shoulders thereon to engage the walls of the mold cavity and adapted to hold in place in the mold cavity an element to be embedded in the casting.

10. A permanent mold for making castings, and comprising a drag and a cope having a mold cavity therein, the drag having oppositely disposed grooves in its parting surface, and a wire arranged in said

grooves and depressed in the cavity to form shoulders engaging opposite walls of the cavity and adapted to hold in place in the mold cavity an element to be embedded in the casting.

11. The combination of a mold for casting a brake shoe comprising a drag and a cope having a mold cavity therein, a reinforcing back to be embedded in the shoe casting and having an opening therein, and a wire extending across the mold cavity and resting on the drag and having a hump cooperating with the opening in the back for holding the back in proper position in the mold cavity.

JAMES S. THOMPSON.
